UNITED STATES PATENT OFFICE.

HENRY G. BUTLER, OF WELLINGTON, KANSAS.

MACHINE FOR PREPARING A BURNING BALLAST-PILE FOR COVERING.

1,212,323.

Specification of Letters Patent.

Patented Jan. 16, 1917.

Application filed November 1, 1911, Serial No. 658,037. Renewed December 1, 1916. Serial No. 134,507.

To all whom it may concern:

Be it known that I, HENRY G. BUTLER, a citizen of the United States of America, residing at Wellington, in the county of 5 Sumner and State of Kansas, have invented certain new and useful Improvements in Machines for Preparing a Burning Ballast-Pile for Covering, of which the following is a specification.

- 10 In the manufacture of burnt clay ballast for railways, a suitable clay bed, approximately rectangular, and containing fifty to one hundred acres, is secured adjoining the railway on which the ballast is to be used. 15 A branch or spur is run from the main line approximately the full length of the site, other spur tracks for the storage of loaded and empty coal cars are also provided and connected by switches to the first mentioned 20 spur track. It is common practice to place the machinery for making the ballast on the track in the following order: first the excavator, second a dragging machine, third a coaling machine, fourth a coal car and fifth 25 a locomotive.

In operation, the work proceeds as follows: First, assume the preliminaries complete and a ballast pile in full operation, say three thousand feet long and awaiting a 30 covering of clay; beginning at the farthest end from the railway switch, the order of procedure should be to drag the burnt mass, then cover with a layer of coal and follow with a coat of clay. But the coal device 35 precedes the dragging device, therefore the following procedure must be followed: the coaling and dragging device moves forward several hundred feet and the dragging of the mass proceeds and progresses toward the 40 end of the fire and the coaling machine follows coaling after the drag. It will be seen therefore that the excavator must stay idle until the first section is completed, and in like manner all repetitions of this procedure 45 as the work progresses compels the excavator to wait on one section until another section is completed. It will be readily seen that a great loss of labor is caused on the 50 excavator, also the dragging and coaling devices lose much time in finishing one strip and starting another, each of the de-

vices having to wait one on the other in starting and finishing a section; further a great loss is sustained by waste of coal on the dragged and coaled portion of the fire,⁵⁵ especially during periods of high wind by reason of the coal burning away before it can be covered with clay, and it is frequently necessary to coal much heavier than ordinarily necessary to burn a coat of clay, and 60 it is sometimes necessary to repeat with a second coaling.

My improved machine is designed to do away with the before mentioned delays and losses, by making the several operations ⁶⁵ simultaneous and continuous, viz: first by dragging, then coaling, followed by a covering of clay.

I accomplish my object by combining on one structure the dragging and coaling mechanism, and transposing thereon the relative positions of the coaling and dragging operations; said transposition can only be accomplished by passing the coal from the railway car past and beyond the dragging device into ⁷⁰ the hopper of the coaling device. I accomplish this object in the manner shown in the accompanying drawings, in which:—

Figure 1 is a plan view of the device with part of the superstructure on the car removed; Fig. 2 is a side elevation of the device viewed from the ballast pile; Fig. 3 shows a broken rear end elevation of the device and a cross section of a ballast pile, and Fig. 4 is a sectional view of the coal ⁸⁰ chute, the dumping cage and the coal bucket in dumped position. Fig. 5 is an enlarged ⁸⁵ end elevation of a hopper car and Fig. 6 is sectional perspective of a valve member for said car.

Similar letters and numbers refer to similar parts in the several views.

A is a railway car on wheels, A' is a rectangular superstructure thereon and A² is a railway coal car.

B is a coal feeding spreading and distributing boom, B' B² are the sides thereof, B² B²— is the bracing and B³ B³ are the rails thereon. B⁴ is the end of said boom and B⁵ B⁵ are sheaves in said end. B⁶ B⁶— ⁹⁵ 100 are baffles hinged to said boom, and B⁷ is the means connecting the baffles.

C is a coal feeding and spreading hopper car with an inclined lower frame, C' on wheels C² C². An upper frame C³ C³ carries the hopper C'. It will be noticed that the frame C³ C³ is longer at one end than at the other end and that the hopper is set to hang vertically with said frame C³ C³ and at an angle with the frame C'. The lower end of said hopper is curved to conform to the curvature and curvital movement of the valve plate c. Said valve plate is attached to brackets c' and said blade is pivotally supported by the shaft c² in the bearings c³ to one of the brackets; at one end of the car is attached a catch lever c⁴ the catch of which engages with the quadrant c⁵.

C⁶ is the cable for hauling car C up boom B, C⁶ is a power driven winding drum on car A and c⁶ is a brake on said drum. D is a drag boom, D' D' are the sides thereof and D² is a sheave in the end thereof. D³ is a drag, D⁴ and D⁵ are cables attached to said drag and to drums D⁶ and D⁷ which are power winding drums on car A; d⁶ and d⁷ are brakes on said drums. The cable D⁵ is passed around sheave D².

E is a coal chute in the superstructure A', and E' is an extension of said chute extending into the railway car A².

E² is a dumping cradle hinged in chute E.

E³ are cables to control the chute E' and are controlled by a winch E⁴.

F is a coal hopper in the superstructure A'. F' is a door in the side of said hopper to control the dumping of coal through chute F² into car C and F³ is a lever and attachments to control said door.

F⁴ is a chute extension of the hopper F.

f is a coal screen extending over the hopper F and the extension F⁴ passing through the end of the hopper and terminating in a chute f'.

f² is a branch of the chute f' and f⁴ is a door to close the opening in hopper F.

f⁵ is a lever and attachments for operating the door f'.

H is a coal unloading boom secured to the superstructure A' and extending over the coal car A².

H' is a sheave in the end of boom H.

I is a coal bucket.

I' and I² are cables fastened at one end to bucket I and at their other ends to the drums I³ and I⁴ respectively in the superstructure A'. i³ and i⁴ are brakes on said drums. Cable I' is looped over the sheave H'.

I⁵ in Fig. 2 shows bucket I in dotted lines in the chute extension E'. J J— are guy cables connecting the booms B, D and H to the superstructure A'.

K is a counterpoise platform and carries the generator K' and counter weight (not shown).

L is a ballast pile in cross section.

L' is the face and L² is the shoulder thereof.

In operation, my improved dragging, intermingling and coaling device works as follows: The operator drops the bucket I into the coal car A² to be filled. He applies power to cable I² through the drum I⁴ and pulls forward and fills said bucket. He then applies brake i³ to drum I³ and by tension on cable I' retards the forward movement of the bucket and the continuation of the winding of the cable I² raises the bucket and by gradually releasing cable I' the bucket is lifted into chute E', as shown in dotted lines I⁵; the bucket is then hauled through chute E onto the cradle E² and the coal dumped on the screen f; a reversal of power from drum I⁴ to drum I³ and tension on brake i⁴, with gradual releasing of said

brake, will return the bucket for reloading. In the burning of ballast coal screenings are used and in the making of said screenings at the coal mine lumps often get into the cars and give trouble in the feeding device in the coal distributing car. To prevent the lumps from getting into said car the coal is screened on the screen f and the slack passed through into the hopper F and the lumps pass into the chute f' and thence to the

ground or into auxiliary chute f² to be used in either case for steam purposes in the several units of the plant. Simultaneous with the process of filling the hopper F, as de-

scribed, the ballast fire is maintained as fol-

lows: Drag D³ is dropped to the bottom of the ballast pile L and by tension on the cable D⁵ by the drum D⁷ is hauled up the face of the pile L' and the mass loosened; after the

drag has passed over the shoulder L² the

power is reversed and applied to drum D⁶ and the drag pulled forward by the cable D⁴ and the shoulder L² pulled over face L. To

continue the operation the device is moved forward the width of the drag and the

process of dragging begins. Simultaneous, however, with the second operation of the drag, coal car C, having previously been

filled with coal from the hopper F is hauled up coal boom B by cable C⁵ on drum C⁶

and when the coal car is over the bottom of the face L' of the pile the controlling mech-

anism on the car is opened and the coal al-

lowed to feed and spread in a ribbon from the coal car to the fire, and by a continuation

of the movement of the coal car the pile is

coaled from bottom to top, or the order may

be reversed and the coal spread from top to

bottom. Sometimes circumstances will arise

when it will be necessary to skip the coaling

of some portion of the face of the pile and if

the coal is wet auxiliary means is necessary

to deflect the coal. For this purpose I use

baffle plates hinged under the coal boom at

regular intervals; they can be triangular or

other forms, but I prefer, for simplicity, the plain baffle plates shown, which consist of plain straight plates of metal or wood; they can be operated singly or collectively by hand, by a man on the top of pile L. It will be readily seen that as soon as my improved device moves a short distance from the end of the ballast pile the excavator can commence covering and the process is continuous until the entire face of the fire is dragged, coaled and covered. After the face of the pile is all under cover the drag is hung up by means of dogs, (not shown) on the drums and the coaling, feeding portions of the device are brought into work to back slack or cover the green coat of dirt with a light layer of coal; the coal thus put on draws or entices the fire to the surface of the clay covering and adds to the rapidity of the burning, but much of said back coaling remains unburned at the time of dragging at which time the drag thoroughly intermingles said coal with the burnt mass and adds to the strength of the fire and helps to finish the process of burning and force the fire through the succeeding coat. (Coaling the ballast pile is called "slacking," and dragging the face and top of the ballast pile is ordinarily termed "working the face and pulling the top.")

What I claim and desire to secure by Letters Patent, is,—

1. In a machine for preparing a ballast fire for covering, the combination of a coal feeding spreading and distributing boom and a coal baffle attached to said boom.

2. In a machine for preparing a ballast pile for covering, the combination of a car structure on wheels, a coal feeding spreading and distributing boom attached to said structure, a coal feeding spreading and distributing car on said boom, coal baffles attached to said boom and means for operating said car and baffles to properly feed, spread and distribute coal on said pile.

3. In an apparatus for ballast burning the combination of a car, a hopper on said car, means for unloading coal from a coal car placed in front of said car, and delivering it to said hopper, a lateral track with a car thereon for conveying the coal from said hopper to be distributed onto the fire, a dragging apparatus on said car for dragging the face of the fire bank.

4. In a machine for ballast burning the combination of a car or movable support, an unloading apparatus at the front of said car for unloading coal from a coal car and delivering it to said car, a boom and a car thereon for conveying the coal from said car to a point over the fire bank, and a dragging or raking apparatus on said car arranged in front of said boom and said car on said boom.

5. In an apparatus for ballast burning the

combination of a car and the structure thereon, a coal hopper in said structure, a coal unloading boom in front of said structure, a coal chute extending from the front of said structure to said hopper, a lateral boom with a coal car thereon for transporting and spreading coal from said hopper over the fire and a drag or raking apparatus on said car arranged in front of said boom and said car on said boom.

6. In an apparatus for ballast burning, a car, means supported by the car for carrying fuel from the car for distribution on a ballast pile, mechanism carried by the car for dragging the pile.

7. In an apparatus for ballast burning, a car, means supported by the car for carrying fuel from the car for distribution on a ballast pile, and dragging mechanism carried by the car in advance of the fuel carrying means for working the ballast pile.

8. In an apparatus for ballast burning, a car, a hopper, means supported by the car for carrying fuel delivered by the hopper from the car for distribution over a ballast pile, and mechanism carried by the car for dragging the ballast pile.

9. In an apparatus for ballast burning, a car, means supported by the car for carrying fuel for distribution on a ballast pile, mechanism carried by the car in advance of the fuel carrying means for dragging the ballast pile, and a hopper carried by the car and arranged to deliver fuel to the fuel carrying means.

10. In an apparatus for ballast burning, a car, a track extending laterally from the car, a distributing car adapted to run on said track for carrying coal for distribution on a ballast pile, and dragging mechanism carried by the car for working the ballast pile.

11. In an apparatus for ballast burning, a car, and means carried by the car for transporting fuel to a ballast pile and having means for effecting distribution of the fuel over the face of the fire from the bottom to the top thereof.

12. In an apparatus for ballast burning, a car, a track extending laterally therefrom, a distributing car adapted to run on said track, and means by which the distributing car can discharge and spread fuel over the face of a ballast pile from the bottom to the top thereof.

13. In an apparatus for ballast burning, a car, means carried by the car for slacking the face and top of a ballast pile, and means carried by the car for working the face and pulling the top of the ballast pile.

14. In an apparatus for ballast burning, a car, mechanisms carried by the car and disposed one in advance of the other, for respectively slacking a ballast pile and for dragging the same.

15. In an apparatus for ballast burning, a

car, a slackening mechanism carried by the car for slackening the ballast pile, and a dragging mechanism carried by the car in advance of the slackening mechanism for working the ballast pile.

16. In an apparatus for ballast burning, a car, and slackening means by which fuel may be spread over the face of a ballast pile,

from the bottom to the top thereof in a continuous sheet or at separated places.

In testimony whereof I affix my signature in presence of two witnesses.

HENRY G. BUTLER.
